UNITED STATES PATENT OFFICE.

MYERS C. CONWELL, OF LARCHMONT, NEW YORK, ASSIGNOR TO LAURA E. CONWELL, OF LARCHMONT, NEW YORK.

AUXILIARY OILER FOR ENGINES.

1,317,961.

Specification of Letters Patent.

Patented Oct. 7, 1919.

Application filed August 18, 1917. Serial No. 186,962.

To all whom it may concern:

Be it known that I, MYERS C. CONWELL, a citizen of the United States, residing at Larchmont, in the county of Westchester and State of New York, have invented new and useful Improvements in Auxiliary Oilers for Engines, of which the following is a specification.

This invention is an apparatus for automatically supplying lubricating oil to engines, and is particularly designed for the lubrication of automobile engines, though not limited thereto.

In the operation of motor vehicles it has been found advisable to maintain a quantity of lubricating oil in the crank case and wheel case, which oil is put into circulation by the operation of the engine, to lubricate the parts of the latter, and various types of control apparatus have been designed to maintain a supply of oil sufficient for this purpose. In such cases, however, if the oil is at a given level when the engine is at rest, this level will immediately drop from one to two inches just as soon as the motor is started, owing to the volume of oil which is carried by the fly wheel and which is in circulation. At the same time, if the pet cock is left open, as is usually necessary with an automatic feed, the oil will run out despite the fact that the actual oil level may be some distance below said cock, and if left open long enough, practically all of the oil, or at least all of the oil within reach of the fly wheel, will be thrown out or lost. This is a cause of many burned out bearings. The reason for the oil being thrown out is that the churning action of the fly wheel beats up the oil to a frothy condition, causing it to bubble out of the pet cock practically as long as there is any oil left. It is this bubbling out or frothing of the oil which renders the operation of a vacuum feed system undesirable for the reason that the froth rises in the air tube, and the air separating therefrom, enters the vacuum chamber and causes more oil to feed down. The main object of the invention is to overcome the foregoing objections by providing an auxiliary oiling apparatus of the vacuum feed type, which will automatically maintain the desired oil level in the crank case and other parts, and absolutely prevent the waste of oil.

The invention will be hereinafter fully

set forth and particularly pointed out in the claims.

In the accompanying drawings;

Figure 1 is a diagrammatic view illustrating the invention applied to an engine of the type commonly employed on the well known "Ford" automobile. Fig. 2 is an enlarged detail view of the stand pipe. Fig. 3 is a diagrammatic view illustrating a modification.

Referring to Fig. 1 of the drawing, 10 designates the engine, which may be of any suitable or preferred type, and 11 the crank case, having the depression 12 in which it is desired to maintain a quantity of oil. The tank or reservoir 13, containing the supply of oil, is supported in any suitable position and in accordance with well known practice, the same being provided with a gage 14, by which the level of oil in the reservoir may be ascertained at a glance. Leading from the reservoir 13, is a feed pipe 15, which is connected by means of a T-coupling 16, with a short branch leading to the bottom of the depression 12. The short branch should communicate with the casing 12, well below the lowest possible working level of the oil, preferably at the bottom of the casing, as shown. Supported in suitable manner contiguous to the casing 12, is a stand pipe 17, provided with a vent pipe 18, at its upper end, open to the atmosphere, the lower end of the stand pipe being connected by a short branch pipe 19, with the coupling 16. The stand pipe 17 is preferably provided with a plurality of threaded nipples 20, as shown, to any one of which is connected the air pipe 21, the other end of which is connected to and communicates with the reservoir 13, above the level of the oil therein. As illustrated in the drawing, the air pipe communicates with the reservoir through the gage 14. The nipples 20, other than the one connected to pipe 21, are closed by suitable plugs 22.

In practice, the tank 13 is filled to the desired level with lubricating oil, and the oil will flow therefrom, through pipe 15 and coupling 16, into the depressed portion 12 of the casing 11, until the level of the oil in said casing reaches the level of the inlet end of pipe 21. It will be understood, of course, that as the oil fills the depressed portion 12 it also fills pipe 19 and is maintained in the stand pipe 17 at the same level as in the

2
depressed portion 12. The level of the oil within the casing 11 depends entirely upon the position of the inlet end of the air pipe 21, and this position may be varied by attaching the air pipe to any one of the nipples 20, to provide high, low or medium levels, as may be desired. As soon as the engine is put into operation the oil level within the depression 12 will be appreciably lowered by reason of the quantity of oil taken up by the working parts of the engine, and just as soon as the level drops below the inlet end of pipe 21, air entering the vent pipe 18, passes up through pipe 21, into the tank 13 or reservoir 13, thereby causing additional oil to flow to the pocket 12, until the level is again raised above the plane of the inlet end of the pipe 21. In this manner a constant level of oil is maintained within the casing 11, and bubbling or frothing of the oil out of said casing is prevented because the supply connection is well below the working level of the oil, and the stand pipe is positioned and connected so as to be unaffected by any agitation of the oil within the casing.

In Fig. 3 is illustrated a slight modification in which a single pipe 25 is utilized as a combined air and oil pipe, said pipe having branches leading respectively to the stand pipe 17 and to the bottom of the casing 12. In this form, when the oil level drops below any portion of the end of pipe 25 where it joins the stand pipe 17, air will move upwardly through said pipe 25 into the tank 13, thereby causing a downward feed of the oil.

Having thus explained the nature of the invention, and described an operative man-

ner of constructing and using the same, although without attempting to set forth all of the forms in which it may be made or all of the forms of its use, the following is claimed:—

1. An auxiliary oiler of the character described comprising a casing to be supplied with oil, a stand pipe spaced from the casing and open to the atmosphere, a conduit leading from the reservoir and having a branch connected to the casing at a point below the lowest normal working level of oil within the casing, and a separate branch leading to the stand pipe. 40 45 50

2. An improved auxiliary oiler comprising a casing to be supplied with oil, a stand pipe open to the atmosphere and communicating with said casing at a point below the lowest normal working level of the oil within said casing, an oil reservoir, an oil supply conduit leading from the reservoir to 60 said casing, and an air pipe communicating with said reservoir, said stand pipe having a plurality of nipples positioned to be selectively engaged by said air pipe. 55 60 65

3. An improved auxiliary oiler comprising a casing to be supplied with oil, said casing being provided with a coupling located below the lowest normal working level of the oil within said casing, a stand pipe open to the atmosphere, a conduit connecting said 70 stand pipe with said coupling, an oil reservoir, an oil supply conduit leading from said reservoir to said coupling, and an air pipe leading from said stand pipe to said reservoir. 75

In testimony whereof I have hereunto set my hand.

MYERS C. CONWELL.
